UNITED STATES PATENT OFFICE

ANDREW R. RIDDERSTROM, OF NAHANT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY

FOLDING MACHINE AND METHOD

Application filed July 17, 1923. Serial No. 652,169.

The present invention relates to methods of and machines for operating upon flexible material, and more particularly to methods of and machines for folding the margins of shoe 5 uppers, such as vamps, quarters, tips and the like.

Folding machines of the above-described character, of the step-by-step-feed type, are provided with a plow which initiates a fold 10 in the margin of the material, and with a fold presser that presses down the fold initiated by the plow. The plows hitherto employed have usually been stationary, upstanding projections by which the margin of the material 15 was literally plowed up as it was dragged past the plow by the feed means. A fold produced in this manner can not, of course, even approximate the one-hundred-eighty-degree bend in the margin that it is the purpose of 20 the folding operation to produce. When the fold is advanced to the fold presser, therefore, there is a tendency for the fold presser to crush the fold rather than to press it flat. To overcome this tendency, a number of ex- 25 peditives have been resorted to. Among these, is the use of creasers that crease the desired line of fold in the margin, and so help the fold presser to press the fold flat along the line of crease. Creasers, however, are but an added 30 complication, and their use is by no means satisfactory. Other additional mechanisms have also been proposed, each having for its object to aid the initial action of the plow. In Letters Patent No. 1,527,391, granted Feb- 35 ruary 24, 1925, the plow is endowed with a back-and-forth movement in the line of feed, rendering such additional aids unnecessary; but, as is explained in Letters Patent Nos. 1,527,394 and 1,527,395, granted on the same 40 date, an additional control of some kind is found desirable in order that the fold presser may press the fold exactly at the desired line or lines, and not to one side thereof.

An object of the present invention is to im- 45 prove upon machines and methods of the above-described character; and to this end, a feature of the invention resides in situating the fold presser immediately forward of the plow in the line of feed, and endowing the 50 plow with a movement transversely to the

line of feed such that the fold initiated thereby shall approximate a one-hundred-and-eighty-degree bend. The fold presser can not but press the fold so initiated flat against the body of the shoe upper at the next feed movement. This construction, furthermore, greatly relieves the stress in the stock resulting from the operation of present-day machines, due to the unnatural twisting that takes place in the margin of the material between the 60 time that it leaves the plow and the time that it reaches the fold presser. 55

The margins of some kinds of shoe uppers are provided with sharply concave or convex curves, during the folding of which it is desirable to slow down the feed. It is not desirable to employ the slow feed in all cases, because straight, or nearly straight, margins should be fed rapidly, in order to save time. The margins of sharply concave uppers, fur- 70 thermore, should be snipped or slit prior to the folding operation, in order to facilitate the folding. Another object of the present invention, therefore, contemplates new and improved means for slowing down the feed and throwing into operation the snipping knife when folding concave margins, and for slowing down the feed without throwing in the knife when operating on convex margins. Certain features of the invention comprise 75 80 also novel means for varying the feed and novel means for controlling the knife.

When the margin is sharply curved, there is a tendency for the operator to feed it out of the range of action of the fold presser 85 after it has been acted upon by the plow and before it has been advanced as far as the fold presser. It is a further object of the present invention to overcome this tendency, and to this end, a feature of the invention resides in 90 building the parts very closely together, in small compass. This is an object that has been most difficult of attainment, in practice.

Other and further objects will be explained in the following description, and will be par- 95 ticularly pointed out in the appended claims, it being understood that the invention consists of the folding method and machine a preferred embodiment of which is illustrated and described herein and that it is intended to 100

express in the appended claims all the novelty that the invention may possess.

In the accompanying drawings, Fig. 1 is a view in side elevation, partly in longitudinal section, of a machine constructed according to a preferred embodiment of the present invention; Fig. 2 is a plan of the forward part of the machine; Fig. 3 is a longitudinal vertical section, taken upon the line 3—3 of Fig. 2, looking in the direction of the arrows; Figs. 4 and 5 are views similar to Fig. 3, showing the parts in different positions; Fig. 6 is a section taken upon the line 6—6 of Fig. 3, looking in the direction of the arrows; Figs. 7 and 8 are views similar to Fig. 6, showing the parts in different positions; Figs. 9 and 10 are longitudinal sections taken upon the lines 9—9 and 10—10, respectively, of Fig. 8, looking in the direction of the arrows, parts being omitted for clearness; Fig. 11 is a transverse section taken upon the line 11—11 of Fig. 9, looking in the direction of the arrows; Fig. 12 is a horizontal section taken upon the line 12—12 of Fig. 1, looking in the direction of the arrows, the section being enlarged with respect to Fig. 1; Fig. 13 is a similarly enlarged section, taken upon the line 13—13 of Fig. 12, looking in the direction of the arrows; Figs. 14, 15 and 16 are sections similar to Fig. 13, showing the parts in different positions; Fig. 17 is a similarly enlarged section taken upon the line 17—17 of Fig. 2, looking in the direction of the arrows; Figs. 18 and 19 are views similar to Fig. 17, showing the parts in different positions; Fig. 20 is an enlarged view of a portion of the improved feed-varying mechanism; Fig. 21 is a vertical section taken upon the line 21—21 of Fig. 20, looking in the direction of the arrows; Fig. 22 is a vertical section taken upon the line 22—22 of Fig. 21, looking in the direction of the arrows; Fig. 22^a is a view of a detail; Fig. 23 is a perspective view of the forward portion of the machine; Fig. 24 is a perspective view of the machine, upon a smaller scale; Fig. 25 is a perspective view of some of the parts shown in Figs. 3 to 7; Fig. 26 is a section taken upon the line 26—26 of Fig. 18, looking in the direction of the arrows; Fig. 27 is a section taken upon the line 27—27 of Fig. 26, looking in the direction of the arrows; Fig. 28 is a perspective view of a modified knife-operating mechanism; Figs. 29, 30 and 31 are elevations of the same, showing the parts in different positions; Fig. 32 is a section taken upon the line 32—32 of Fig. 28, looking in the direction of the arrows; Fig. 33 is a section taken upon the line 33—33 of Fig. 1, looking in the direction of the arrows; Fig. 34 is a plan, partly in section, of a portion of the mechanism shown in Fig. 5; Fig. 35 is a view showing a preferred plow control; Fig. 36 is an elevation, looking in the direction of the arrows of the line 36—36 of Fig. 35; and Fig. 37 is a section

taken upon the line 37—37 of Fig. 36, looking in the direction of the arrows.

The invention is illustrated as applied to a folding machine for folding the margins of shoe uppers, such as vamps, quarters and the like. The machine is provided with a lower feed block 41 and an upper feed point 30, shown more particularly in Figs. 6, 7 and 8, between which a sheet of flexible material, like a shoe upper 2, is intermittently gripped, and by which the sheet is fed or advanced, step by step over a platform or support 24, to a folder or plow 32 that initiates a fold in successive portions of the margin of the material. A fold presser 42 presses the fold flat against the body of the upper 2 during pauses in the feed. The fold presser is situated immediately forward of the plow, and the plow folds the margin nearly one hundred eighty degrees, or almost flat against the body of the upper, as will be understood from Figs. 3 and 5, before the fold is advanced by the feed means to the fold presser.

The fold presser 42 is floatingly pivoted at 146, Figs. 3 to 5, to one end of a link 148 the other end of which is eccentrically connected by a pin 150, Fig. 1, to a spiral gear 152 meshing with a spiral gear 154 upon a driving shaft 66. By means of the construction illustrated in the drawings and explained at length in the above-mentioned Letters Patent No. 1,527,395 and also Letters Patent No. 1,527,396, the fold presser is pivotally actuated in a plane at right angles to the plane of feed, with a yielding action of the fold presser upon the fold, relieving the stress thereon.

As it is desired to have the parts positioned very closely together, there is very little space available in which to mount operating mechanism for the plow. It is accordingly found convenient to operate the plow from the fold presser, as will now be described.

The platform or support 24 is secured to a separable cap 4 at the left-hand end of the machine, as viewed in Figs. 3 and 23, by a screw 6. The cap is, in its turn, secured to the frame of the machine by screws or the like 8. The upper portion of the cap 4 is provided with a longitudinally extending opening 10, within which is secured a longitudinally disposed block 12 by the same screw 6 that holds the support 24 in place, as is clearly shown more particularly in Figs. 3, 4, 5 and 23. The block 12 is thus, in effect, secured to the under side of the support 24. The plow 32 is pivoted at 130 to an inwardly projecting portion 14 of the block 12 in such fashion as to pivot in a plane that is longitudinally disposed with respect to the machine, or that is at right angles, or transverse, to the line of feed.

A spring is employed to maintain the plow 32 in a limiting position of its pivotal movement. In the modification of Figs. 3, 4 and 5, the spring 132 is shown as of the coiled type,

- with projecting ends respectively secured at 136 on the arm 160, and at 137 on the plow 32. A spring of this type, and so secured, seems to have a tendency to break. It is therefore preferred to employ one or more leaf springs 16, shown more particularly in Figs. 35, 36 and 37. The leaf spring or springs 16 may be secured at one end in a recess 18, adjacent to the opening 10, by a screw or the like 20, and the other end may engage a projecting pin 22 or other part projecting from the plow 32. Whether the construction of Figs. 3, 4 and 5 or that of Figs. 35, 36 and 37 be employed, the plow 32 will be maintained yieldingly in the limiting position shown more particularly in Figs. 3, 5, 35, 36 and 37. Of course, any equivalent construction may equally well be employed for effecting the same result.
- 20 To actuate the plow 32 about its pivotal point 130, in opposition to the force exerted by the springs 16 or 132, the fold presser is provided with a portion 144 that extends rearward in the line of feed and to one side of a forwardly projecting portion 140 of the plow, as is shown more particularly in Figs. 6, 7 and 8. During the return movement of the fold presser, therefore, the portion 144 engages the forwardly projecting portion 140 of the plow 25 and cause it to pivot about its pivotal point 130, as is clearly shown in Fig. 4. During the fold-pressing movement of the fold presser, indicated by the curved arrow of Fig. 3, the spring or springs 16 or 132 will cause the plow 30 to move with the fold presser, as indicated in Fig. 3. During the further movement of the fold presser, from the position of Fig. 3 to that of Fig. 5 the plow 32 can not follow the fold presser, but will be maintained in its limiting position by the spring or springs 16 or 35 132 until the next return movement of the fold presser.
- It has been explained that the portion 144 of the fold presser extends rearward in the line of feed and to one side of the forwardly projecting portion 140 of the plow. The forwardly projecting portion 140 of the plow does not have any plow function. The portion 144 of the fold presser does, however, serve to 40 press the fold previously initiated by the plow. As will be clear from the drawings, and more particularly Figs. 6, 7 and 8, the portion 144 of the fold presser extends rearward as close as possible to the fold-initiating portion of the plow. The fold presser is therefore situated immediately forward of the plow in the line of feed and, as the plow pivots in a plane at right angles to the line of feed, so as to produce a bend of nearly one hundred 45 eighty degrees, the fold presser necessarily presses the fold so initiated flat against the body of the shoe upper along the line of fold that is thus predetermined by the plow.
- Summarizing the operation of the machine as thus far described, the shoe upper 50
- is advanced over the support 24, step by step, by the feed point 30 and the feed block 41; the plow 32 is pivotally actuated in a plane at right angles to the line of feed during pauses in the feed to initiate a fold in successive portions of the margin, step by step; and the fold presser 42, situated immediately before the plow in the line of feed, is actuated step by step, during pauses in the feed, to press flat the folds successively initiated by the fold presser during immediately prior pauses in the feed. Each folded portion is pressed while the next succeeding portion is being folded, thereby relieving the strain in the material. The fold presser and the plow are actuated as a unit during a portion of the actuation of the fold presser in planes at right angles to the line of feed, the fold presser being actuated during the remainder of its cycle of operation alone. The plow is not, however, rigidly secured to the fold presser, but is yieldingly connected thereto. This yielding connection not only permits the fold presser and the plow to be actuated as a unit at times, thereby further relieving the strain upon the margin during folding and pressing, and separately at other times, but it provides for the plow yielding with respect to the fold presser during the actuation of the fold presser and the plow, when unusually thick places in the stock, such as seams, are encountered. It is within the scope of the present invention to have the plow of straight formation. It is more effective, however, to provide the plow with a nose 34 and a concavity 134 adjacent to the nose. The nose is adapted to engage the margin of the material during the actuation of the plow, in a manner that will be clearly understood more particularly from Fig. 4, and the curve of the fold thus formed will be adapted to seat in the concavity 134, as will be understood from Figs. 3 and 5. The margin of the support 24 adjacent to the concavity 134 is inclined or curved upwardly towards the concavity 134, as shown at 26, to cooperate with the concavity 134 in the seating of the fold. A retainer 153 holds the stock against the support during the pauses in the feed. The other functions performed by the retainer, and the retainer-operating mechanism, will not be described herein, because fully described in the above-referred-to Letters Patent No. 1,527,395, and because other retainers and other retainer-operating mechanisms may also be employed without departing from the present invention. The retainer of the present invention, however, is situated preferably immediately to the rear of the folding nose 134 of the plow 32. The retainer, the plow and the fold presser are thus positioned very closely together, in small compass, enabling operation upon stock having very sharp corners. This positioning of 130

the plow immediately before the retainer, furthermore, enables the nose of the plow to initiate the fold more easily. This is because the upstanding arm 246 of the retainer acts as a kind of drag against which the nose of the plow causes the margin of the stock to be twisted during the initiation of the fold. This twisting action naturally aids the plow in bending the successive portions of the 10 margin through so large an angle as nearly one hundred eighty degrees, and thus aids the plow in properly presenting the stock to the fold presser for action by the latter. The corner edge of the retainer, near the 15 plow, should be round, and not sharp.

It has been explained that the fold presser is driven from a spiral gear 154 upon the driving shaft 66. The driving shaft 66 is driven by mechanism under the control of 20 the operator, shown in Fig. 1, and more fully described in the above-named Letters Patent No. 1,527,395. The feeding mechanism, comprising the feed block 41 and the feed point 30, is also driven from the driving shaft 66. The feed block 41 is shown more particularly in Fig. 9 as rigidly secured to, or 25 integral with, a holder 93 that is secured, as by a set screw, to a rocking or oscillating support 94. The rocking support is pivotally mounted about a rod 96 that is secured to the frame of the machine by a screw 98. The feed point 30 is pivotally mounted at 30 110 upon the rocking support 94, so as to be rocked therewith and with the lower feed block 41.

An arm member 36 is also pivotally mounted to rock or oscillate about the rod 96. The member 36 is provided with a diagonally disposed, cylindrical opening 100, shown more particularly in Figs. 9 and 11, within which is slidingly mounted a diagonally cylindrical block 102 the upper flat face of which is substantially horizontal, as shown at 104. The angle of inclination of the opening 100 is 40 preferably in the neighborhood of thirty degrees. The cylindrical block 102 is adapted to be actuated by an eccentric or crank pin 106 of the driving shaft 66. The eccentric or crank pin is rotatably mounted in the block 102 and extends through an opening 108 of the rocking member 36. Rotative movement of the shaft 66 will be converted by the eccentric into combined sliding and oscillating or rotative movement of the block 102 45 and this, in turn, will effect a rocking movement of the rocking member 36 about the rod 96. A compression coiled spring 38, interposed between the rocking support 94 and the rocking member 36, yieldingly connects the 50 rocking support 94 to the rocking member 36 to cause them to rock or oscillate together, as a unit. The coiled spring 38 yieldingly maintains an arm 39 of the rocking support 94 in engagement with an adjustable portion 55 40 of the rocking member 36. The adjust-

able portion 40 of the rocking member 36 is shown as a set screw.

The feed point 30 is normally yieldingly maintained in contact with the feed block 41 by a compression coil spring 112 coiled about 70 a threaded rod 114 extending through an opening 116 in the feed-point arm 118 and secured at 43 to the rocking support 94. By means of the threads upon the rod 114, the pressure of the spring 112 upon the feed point may be adjusted, the ends of the spring being confined between the feed-point arm 118 and a knurled nut 124 that is threaded upon the rod 114. The feed-point arm 118 is provided with an adjustable screw 120. 80 The upper face 104 of the block 102 is adapted to engage the screw 120, thereby to raise the feed point in opposition to the pressure of the spring 112. An additional adjustable member 123 is provided to prevent the feed point becoming lowered into contact with the feed block when the machine is running idly, thereby preventing the feed point pounding uselessly against the feed block 85 when no stock is interposed.

As the driving shaft 66 is rotated, the rocking support 94 is rocked from right to left and from left to right, as viewed in Fig. 11, imparting an oscillating movement to the lower feed block 41 and the upper feed point 30 which are carried thereby. During the left-to-right movement, the feed point 30 will be separated from the feed block 41 by the action of the cylindrical block 102, which then occupies its upper positions. During the right-to-left movement, the block 102 will lie in the lower portions of the cylindrical opening 100, and the feed point will be spring-pressed into engagement with the feed block, which will thus advance to the 90 fold presser the upper clamped therebetween. 100

Curved portions of the work should not be fed so rapidly as straight portions. The above-described construction affords a novel means of varying the lengths of the feed 110 steps, so as to feed the work by greater or by shorter feed strokes, at will. To this end, all that is necessary is to adjust angularly the rocking support 94 closer to, or farther from, the rocking member 36. The limits of oscillation of the rocking member 36 are, of course, fixed; but the farther away from the rocking member 36 that the rocking support 94 is adjusted, the farther to the left, as 115 viewed in Fig. 11, will the rocking support 94, with the feed point and the feed block carried thereby, oscillate. The limit of oscillation towards the left may be fixed initially by means of the screw 40, and this will 120 determine the maximum length of the steps of feed. The steps may then be shortened during the operation of the machine by pressing the rocking support 94, or the arm 39 125 thereof, in opposition to the force exerted by 130

the spring 38, towards the right, as viewed in Fig. 11.

This is accomplished, according to the embodiment of the invention that is herein illustrated and described, by pressing upward and to the right, in the direction of the curved arrow, Fig. 11, about the rod 96, upon an arm 45 that projects out from the arm 39 of the rocking support 94. The free end of the arm 45 is adapted to be engaged by the free end of an arm 122 that is pivoted to the frame of the machine at 143. Pivotal movement of the arm 122 may be effected by a vertically disposed arm 145, the upper end of which is 15 pivoted to the arm 122 at 147. The lower portion of the arm 145 is adapted to be engaged by either of two cams 29 and 31, shown more particularly in Fig. 22^a as provided upon a single cam member 46. Rocking the 20 cam member 46 in either direction will cause the cam 29 or the cam 31, as the case may be, to raise the arm 145. Raising the arm 145 will effect pivotal movement of the arm 122, the free end of which will engage the arm 45 to 25 press the latter upward, thereby adjustably limiting the length of the feed steps. The action may be adjusted by means of an adjustable member 149, shown as a screw, mounted at the free end of the arm 122.

30 The cam 29 has a higher throw than the cam 31. The cam 29 therefore permits of a more rapid adjustment than the cam 31, and provides also for a greater range of adjustment. As will shortly appear, either cam 35 may be actuated to any desired degree up to a maximum, adjustable limit. To actuate the cam member 46, it is secured to one end of a rock shaft 151 that extends transversely across the machine, as shown more particularly in Fig. 2, and to the other end of which is secured a lever 176. The lever 176 is connected by a link 178, Figs. 2 and 24, to a lever 179 that is secured to a rock shaft 188. The rock shaft 188 is provided with two fixed 40 arms 183 and 185 that are respectively connected to treadle rods 187 and 189. By actuating one or the other treadle rod, the rock shaft 188 will be rocked in one or the other direction, and the rocking movement of the 45 rock shaft will be communicated, through the link 178 and the lever 176, to the rock shaft 151, thereby rocking the cam member 46 in one or the other direction. The treadle rods 187 and 189 may be connected to opposite 50 ends of a single treadle (not shown).

Before the machine is started, it is desirable to raise the feed point from the feed block to permit the insertion of the upper therebetween. A preferred construction for 55 raising the feed point is illustrated in Figs. 2 and 9. The feed point is adapted to rest upon the screw 123, as before described, but it is adapted to be raised therefrom by a rod 300 that is vertically disposed in an opening 302 of the rocking support 94. The rod 300

rests upon the head of a rod 304 that is slidably mounted in a vertical opening 306 provided transversely through the rod 96. To raise the feed point, therefore, it is only necessary to raise the rod 304. The rod 304 70 is adapted to be raised by an adjustable member 312 at one end of a lever 307 pivoted at 308 and that is normally maintained in the illustrated position by a weight 310 that is adapted to rest against an adjustable member 315. A handle 313, that extends through an opening 316 in the frame of the machine, is adapted to be actuated by the operator so as to cause the raising of the rods 304 and 300 and, through them, of the feed point 30. 80

In the above-described manner, the rocking member 36 and the rocking support 94 may be rocked or oscillated as a unit, provision being made, however, for adjustably limiting the degree of oscillation of the rocking support 94 and, therefore, adjustably limiting the lengths of the feed steps of the feed block 41 and the feed point 30 that are carried by the rocking support 94. The treadle rods 187 and 189 provide for operating the rock 90 shafts 151 and 188 in opposite directions to effect a variation in the lengths of the feed steps in the same direction,—namely, a shortening or diminution of the feed steps. An 95 advantage of this construction will presently be described. It will be desirable to explain first, however, the preferred snipping or slitting mechanism.

The slitting is performed, according to the preferred embodiment of the present invention, by a movable knife 352, cooperating with a stationary knife 353, and situated immediately in the rear of the retainer 153, at a position to one side of the feed elements at their forward limit of feed movement, as is illustrated in Fig. 7, but forward of the position of the feed elements at their rearward limit of feed movement, as is illustrated in Fig. 8. The movable knife 352 is pivoted to the upper end of a bracket 61 and is connected at 356 to one end of a link 354. The other end of the link 354 is adapted to be clutched to, and unclutched from, knife-operating mechanism, so as to cause the knife 100 to be actuated or idle, at the will of the operator. 105

The preferred clutching mechanism is illustrated in Figs. 1 and 12 to 16. Modifications are shown in Figs. 28 to 34. According 110 to the preferred construction, the said other end of the link 354 is adjustably connected to a plate-like member 362 that is adapted to be clutched to a gear 366 that is driven from the gear 154 upon the driving shaft 66. The 115 illustrated details of the adjustable connection between the link 354 and the plate-like member 362 comprise slots 368 in the link 354 and set screws 370 that are adapted to enter the slots and bind the link 354 against 120 125 130

the plate-like member 362. The holding action may be increased by means of ribs 372 or the like upon the two members to prevent accidental slipping.

The plate-like member 362 is provided with a polygonal-shaped, parallel-sided, opening 374 within which is slidably mounted a correspondingly shaped polygonal block 376. The block 376 is loosely mounted upon an eccentric 378 of the gear 366. Rotative movement of the gear will, therefore, through the eccentric 378, be converted into reciprocating movement of the block 376 within the opening 374. The sliding movement of the block 376 within the opening 374 may be prevented by means of a clutch cam 380 that is fixed to the eccentric 378 and that is adapted to be adjusted so as to bind against a pin 382, as shown in Fig. 15. A set screw 384 may be employed to bind against the block 376 at a point on the other side of the eccentric. The block 376 being thus held against movement in the slot 374, the movement of the eccentric 378 will now be transmitted to the link 354 and, through the link, to the knife 352. A very effective clutching of the knife to the gear 366 is thus obtained.

To adjust the clutch cam 380 into and out of clutching engagement with the pin 382, the eccentric is loosely rotatably mounted in a bearing 386 that extends through the gear 366, as shown more particularly in Fig. 12, and its rearward projecting end is fixed to a lever 388, as is shown more particularly in Fig. 24. The lever 388 is connected by a link 390 to the lever 179, and is therefore controlled by the same treadle rods 187 and 189 that control the feed variation. Actuation of the treadle rod 187 will effect a movement of the knife-clutching cam 380 from the position of Fig. 13 to the positions of Figs. 14 and 15. Actuation of the treadle rod 189 will effect a movement of the knife-clutching cam 380 in the opposite direction. The treadle rod 187 therefore controls both the action of the knife and the variation of the feed. The treadle rod 189, on the other hand, controls the feed variation alone. As the treadle rod 187 renders the cam 31, and the treadle rod 189 the cam 29, effective to vary the feed, it will now be understood that when the knife is thrown into operation, the feed steps will also be shortened, but to a smaller degree than when the treadle rod 189 is rendered effective. Of course, this relation might readily be reversed by changing the relative positions of the cams 29 and 31. The knife is usually thrown into operation when concave margins are folded, for concave margins should be snipped prior to folding. When feeding concave margins, the feed should be slowed down, which is accomplished in the illustrative machine. It is equally desirable to slow down the feed when folding convex margins, but convex margins need not be snipped. The

treadle rod 189 may therefore be employed when folding convex margins, and the treadle rod 187 when folding concave margins. The treadle rod 189, by withdrawing the clutching cam 380 from clutching position, automatically renders the knife ineffective, as the block 376 thereupon begins to reciprocate idly in the opening 374. A spring 392 may, however, be employed positively to actuate the knife 352 to the open position, illustrated in Fig. 17.

The limits of movement of the treadle rods 187 and 189 may be adjustably controlled by adjustable stop screws 394 and 396, Fig. 24, secured to arms 398 and 400 that are rigidly secured to the rock shaft 188 and acting against abutments 402 and 404 provided upon the frame. Any intermediate movement short of these limiting movements may, of course, be imparted to the treadle rods, but the feed steps will not, in that event, be shortened by quite so great an amount. If the cam 380 be actuated, not to the limiting position shown in Fig. 15, for example, but to the intermediate position shown in Fig. 14, the knife 352 will cut snips of not so great depth, and the feed steps will be shortened by not quite so great an amount. The cutting position of the knife corresponding to the clutch-cam position of Fig. 14 is illustrated in Fig. 18, Fig. 19 corresponding to the clutch-cam position of Fig. 15. The present invention therefore provides means for varying the depth of the snip cuts in accordance with the spacing of the cuts. It will be noted that the construction is such that the knife is thrown into operation somewhat after the feed is varied. Instead of controlling the knife and the feed variation by treadles, the control may be effected by the operator's knee. The knee may be placed between arms 406 and 408, Fig. 1, provided at the lower end of a rocking shaft 410 that is disposed in a vertical bearing 412. The upper end of the shaft 410 is connected by a universal joint 414 to one end of a link 416 the other end of which is connected by a universal joint 418 to the arm 179. By moving the knee to the left or the right, therefore, the shaft 410 will be rocked in the one or the other direction, effecting the same control over the feed and the knife as before described. It may be desirable to control either the feed alone or the knife alone by a foot-treadle, and the other by the knee, and either of these combinations may readily be effected. By disconnecting the link 390 from the lever 179, for example, and connecting the link 416 to the link 390, the knife may be controlled by the knee alone, and the feed variation by the treadle alone.

The stationary knife 353, with which the movable knife 352 cooperates, is mounted at an incline to the plane of the support 24, as will be understood from Figs. 17, 18, 19 and 23. The arrangement of the two knives is

such that the knife 352 need move but very little, from the position of Fig. 17 to the position of Fig. 19, in order to effect a full cutting stroke. The danger of the operator cutting his fingers is thus eliminated. The knife 353 is integrally provided with a stem 420, Fig. 27, that extends through an opening 422 in the bracket 61, and the free end of which is provided with a screw-threaded opening 5 adapted to receive a locking screw 424. When the knife 353 becomes dull, the stem 420 is pushed out of the opening 422, the knife is sharpened, and the stem 420 is replaced and relocked in its opening 422. The knife 353 10 should not be ground parallel to the original cutting edge, but at an angle thereto, so as to retain always the position of the end shoulder 426. In order that the knife 353 may occupy its former position after grinding, 15 the knife should be turned about the axis of the stem 420 when it is replaced in position. In this manner, the effective cutting edge of the knife 353 may be retained always in the same position, no matter how often it has 20 been sharpened.

As the stationary knife 353 occupies an inclined position, it is desirable to feed the stock thereto with its margin correspondingly bent out of its plane. The initial bend thus 25 imparted to the margin is further advantageous in relieving, by so much, the stress that is later imposed by the plow in its folding action upon the margin. To bring this result about, the bracket 61 is provided with an inclined portion 428 on which the margin is adapted to rest, and by which it is bent 30 slightly out of the plane of the shoe upper, as the upper is advanced by the feed point and the feed block. The inclined portion 428 is 35 situated to one side of the feed block 41, and the feed point 30 is provided with a correspondingly inclined finger 430 for holding the margin against the inclined portion 428 during the feeding of the material. The inclined portion 428 is somewhat more deeply 40 curved in the center, at 432, than near the ends, so as to provide for a sharper rise towards the knife 353 at 434. A gage 436, secured by a screw at 438, is provided just 45 rearward of the knife 353, in order to gage the advance of the margin of the upper to the knives.

A modified knife control is shown in Figs. 28 to 32. The link 354 is shown pivoted at 50 to the free end of an arm 452 that may be adjusted angularly with respect to the gear 366. A polygonal block 454, similar to the block 376, is adapted to slide in a polygonal opening 456, similar to the opening 374, in the arm 452. An eccentric 458 of the gear 366 is adapted to actuate the block 454, as in the preferred construction. The arm 452 is pivoted at 460, near the circumference 55 of the gear 366, to an arm 462 that is angularly adjustable about the axis of the gear 366.

Obviously, if the pivotal point 460 and the eccentric 458 are in a line nearly at right angles to the link 354, as in Fig. 29, the link 354 will be oscillated through a larger path than when the pivotal point 460 and the eccentric 458 are nearly in line with the link 354, as shown in Fig. 31. In the latter case, the reciprocation of the link 354, and the consequent movement of the knife 352, will be very little, if any; in the former case, the movement of the knife 352 will be measured by the angle between the two lines 463 and 464 that converge to the pivot 460, and is indicated by the distance between the points of the arrows 466 in Fig. 29. An intermediate adjustment of the point 460 is indicated in Fig. 30, and the corresponding range of movement of the knife 352 is indicated by the distance between the points of the arrows 468. The angular position of the pivotal point 460 may be adjusted by angularly adjusting the arm 462 about the axis of the gear 366. This may be effected by adjusting a link 470 one end of which is pivoted to an arm 472. The arms 462 and 472 are integrally connected to a hub 474 that is rotatable about the axis of the gear 366. The link 470 may be connected to the arm 179, Figs. 24 and 32, so as to be treadle- or knee-controlled. The arm 179 is adapted to actuate the link 354 in opposition to the force exerted by a spring 476. The ends of the link 470 are adapted to move in curved guides 478 and 480, the latter guide being concentric with the axis of the gear 366 and the former being 60 parallel with the latter.

Many details of the illustrative machine have not been illustrated herein, and many illustrated parts have not been described, because unnecessary to an understanding of the present invention, and because full particulars may be obtained in the aforesaid Letters Patent. The elements of novelty, furthermore, though fully explained, are by no means restricted to the exact embodiments thereof 65 that are illustrated and described herein. Modifications and changes will readily occur to persons skilled in the art, and all such are considered to fall within the scope of the invention, as defined in the appended claims. 110

What is claimed is:

1. A folding machine having, in combination, means for feeding material, a folder for folding the material in one step through an angle of nearly one hundred eighty degrees, 120 and a fold presser situated immediately before the folder in the direction of the line of feed for pressing the fold produced by the folder, the fold presser and the folder being immovable relatively to each other in the 125 direction of the line of feed.

2. A folding machine having, in combination, means for feeding material, a folder for folding the material in one step through an angle of nearly one hundred eighty degrees, 130

- means for actuating the folder to fold successive portions of the material each in one step, a fold presser situated immediately before the folder in the direction of the line of feed, the fold presser and the folder being immovable relatively to each other in the direction of the line of feed, and means for actuating the fold presser to press the folds successively produced by the folder. 5 70
10. A folding machine having, in combination, means for feeding material, a folder for folding the material in one step through an angle of nearly one hundred eighty degrees, means for actuating the folder in a direction transverse to the direction of the line of feed 75
15. during the operation of the machine, and a fold presser situated immediately before the folder in the direction of the line of feed for pressing the fold produced by the folder. 80
20. 4. A folding machine having, in combination, means for feeding material, a folder for folding the material in one step through an angle of nearly one hundred eighty degrees, the folder being pivoted to move in a plane at 85
25. right angles to the direction of the line of feed during the operation of the machine, and a fold presser situated immediately before the folder in the direction of the line of feed for pressing the fold produced by the folder. 90
30. 5. A folding machine having, in combination, means for feeding material, a plow for initiating a fold in the margin of the material, a fold presser for pressing the fold initiated by the plow, and means for actuating 95
35. the fold presser and the plow as a unit. 100
6. A folding machine having, in combination, means for feeding material, a plow for initiating a fold in the margin of the material, a fold presser for pressing the fold initiated by the plow, and means for pivotally actuating the fold presser and the plow as a unit in a plane at right angles to the line of feed. 110
15. 7. A folding machine having, in combination, means for feeding material, a plow for initiating a fold in the margin of the material, a fold presser for pressing the fold initiated by the plow, means for actuating the fold presser and the plow as a unit, and means 115
20. whereby the plow is adapted to yield with respect to the fold presser during the actuation of the fold presser and the plow as a unit. 120
25. 8. A folding machine having, in combination, means for feeding material, a plow for initiating a fold in the margin of the material, a fold presser situated immediately before the plow in the line of feed for pressing the fold initiated by the plow, means for pivotally actuating the fold presser in a plane 125
30. at right angles to the line of feed, and means yieldingly connecting the plow to the fold presser, whereby the plow is adapted to be actuated with the fold presser and is adapted to yield with respect to the fold presser during the actuation of the fold presser. 130
9. A folding machine having, in combination, a support, means for feeding material over the support, a plow for initiating a fold in the margin of the material pivoted to the support so as to move pivotally in a plane at right angles to the line of feed, a fold presser for pressing the fold initiated by the plow, means for pivotally actuating the fold presser in a plane at right angles to the line of feed, and means yieldingly connecting the plow to the fold presser, whereby the plow is adapted to be actuated with the fold presser and is adapted to yield with respect to the fold presser during the actuation of the fold presser. 70
10. A folding machine having, in combination, a plow for initiating a fold in the margin of a piece of material, means for actuating the plow transversely to the margin of the material, the plow having a nose adapted to engage the margin of the material and a concavity adjacent to the nose in which concavity the curve of the fold is adapted to seat during the actuation of the plow transversely to the margin. 85
11. A folding machine having, in combination, a support, a retainer for holding material against the support, a plow for initiating a fold in the margin of the material, means for pivotally actuating the plow transversely to the margin of the material, the plow having a nose adapted to engage the margin of the material at one side of the retainer and a concavity adjacent to the nose in which concavity the curve of the fold is adapted to seat during the actuation of the plow transversely to the margin. 90
12. A folding machine having, in combination, a support, means for feeding material over the support, a retainer for holding the material against movement upon the support, a folder for folding the material in one step through an angle of nearly one hundred eighty degrees, the folder being situated before the retainer in the direction of the line of feed, and a fold presser for pressing the fold produced by the folder. 105
13. A folding machine having, in combination, a support, means for feeding material over the support, a retainer for holding the material against the support, a folder for folding the material in one step through an angle of nearly one hundred eighty degrees, the folder being situated immediately before the retainer in the direction of the line of feed, and a fold presser for pressing the fold produced by the folder situated immediately before the folder in the direction of the line of feed, the fold presser and the folder being immovable relatively to each other in the direction of the line of feed. 110
14. A folding machine having, in combination, means for feeding material, a plow held from movement in the line of feed for initiating a fold in the margin of the material, and a 115

- fold presser situated immediately before the plow in the direction of the line of feed for pressing the fold initiated by the plow, the fold presser having a portion extending rearward in the direction of the line of feed and to one side of the plow. 70
15. A folding machine having, in combination, means for feeding material, a plow for initiating a fold in the margin of the material adapted to be actuated pivotally in a plane at right angles to the line of feed, a fold presser situated immediately before the plow in the line of feed for pressing the fold initiated by the plow, means for pivotally actuating the fold presser in a plane at right angles to the line of feed, the fold presser having a portion extending rearward in the line of feed and to one side of the plow, and means yieldingly maintaining the plow in engagement with the extending portion of the fold presser, whereby the plow is adapted to be actuated with the fold presser and is adapted to yield with respect to the fold presser during the actuation of the fold presser. 75
15. A folding machine having, in combination, a support, means for feeding material over the support, a retainer for holding the material against the support, a plow for initiating a fold in the margin of the material situated immediately before the retainer in the line of feed, the plow being adapted to be actuated pivotally in a plane at right angles to the line of feed, a fold presser situated immediately before the plow in the line of feed for pressing the fold initiated by the plow, means for pivotally actuating the fold presser in a plane at right angles to the line of feed, the fold presser having a portion extending rearward in the line of feed and to one side of the plow, and means yieldingly maintaining the plow in engagement with the extending portion of the fold presser, whereby the plow is adapted to be actuated with the fold presser and is adapted to yield with respect to the fold presser during the actuation of the fold presser. 80
25. 16. A folding machine having, in combination, a support, means for feeding material over the support, a retainer for holding the material against the support, a plow for initiating a fold in the margin of the material situated immediately before the retainer in the line of feed, the plow being adapted to be actuated pivotally in a plane at right angles to the line of feed, a fold presser situated immediately before the plow in the line of feed for pressing the fold initiated by the plow, means for pivotally actuating the fold presser in a plane at right angles to the line of feed, the fold presser having a portion extending rearward in the line of feed and to one side of the plow, and means yieldingly maintaining the plow in engagement with the extending portion of the fold presser, whereby the plow is adapted to be actuated with the fold presser and is adapted to yield with respect to the fold presser during the actuation of the fold presser. 85
25. 17. A folding machine having, in combination, a support, means for feeding material over the support, a retainer for holding the material against the support, a plow for initiating a fold in the margin of the material pivoted to the support immediately before the retainer in the line of feed so as to move pivotally in a plane at right angles to the line of feed, the plow having a nose adapted to engage the margin of the material at one side of the retainer and a concavity adjacent to the nose in which concavity the curve of the fold is adapted to seat during the pivotal actuation of the plow in its plane at right angles to the line of feed, a fold presser situated immediately before the plow in the line of feed for pressing the fold initiated by the plow, means for pivotally actuating the fold presser in a plane at right angles to the line of feed, 90
- the fold presser having a portion extending rearward in the line of feed and to one side of the plow, and means yieldingly maintaining the plow in engagement with the extending portion of the fold presser, whereby the plow is adapted to be actuated with the fold presser and is adapted to yield with respect to the fold presser during the actuation of the fold presser. 95
18. A machine of the class described having, in combination, a continuously rotating member having an eccentric, a block mounted loosely on the eccentric, a member having an opening within which the block is mounted to slide freely, and means for holding the block against sliding movement in the opening to cause the second-named member to move with the continuously rotating member. 100
19. A machine of the class described having, in combination, a continuously rotating member having an eccentric, a polygonal block mounted loosely on the eccentric, a member having an opening within which the polygonal block is mounted to slide freely, means for holding the block against sliding movement in the opening to cause the second-named member to move with the continuously rotating member, and a knife connected to the second-named member. 105
20. A machine of the class described having, in combination, means for feeding material, means for varying the feed of the material, normally ineffective means for cutting the material, a clutch for rendering the cutting means effective, and means operable first to set the feed-varying means into operation and then to actuate the clutch to effective position. 110
21. A machine of the class described having, in combination, means for feeding material, means for varying the feed of the material, means for cutting the material and means operable in one direction to set into operation the feed-varying means and the cutting means and in another direction to set into operation the feed-varying means without the cutting means. 115
22. A folding machine having, in combination, means for folding the margin of material, normally ineffective means for slitting the margin prior to folding, a clutch for rendering the slitting means effective, means for feeding the material to the slitting means and the folding means, means for varying the feed of the material, and means operable first to set the feed-varying means into operation and then to actuate the clutch to effective position. 120
23. A folding machine having, in combination, means for folding the margin of material, means for slitting the margin prior to folding, means for feeding the material to the slitting means and the folding means, means for varying the feed of the material, and means operable in one direction to set 125
65. 130

into operation the feed-varying means and the cutting means and in another direction to set into operation the feed-varying means without the cutting means.

24. A folding machine having, in combination, means for folding the margin of material, a knife for slitting the margin prior to folding, a continuously rotating member having an eccentric, a block mounted loosely on the eccentric, a member connected to the knife having an opening within which the block is mounted to slide freely, means for holding the block against sliding movement in the opening to cause the knife-connected member to move with the continuously rotating member, means for actuating the holding means, means for feeding the material to the knife and the folding means step by step, means operable in two directions for diminishing the lengths of the steps of feed, and means operable in one direction for operating the actuating means for the holding means and for operating the step-diminishing means in one of the said two directions, the said operating means being operable in another direction for operating the step-diminishing means in the other of the said two directions without also operating the holding means.

25. A folding machine having, in combination, a support, means for feeding material over the support, a retainer forward of the feeding means in the direction of the line of feed for holding the material against the support, a plow immediately forward of the retainer in the direction of the line of feed for initiating a fold in the margin of the material, and a fold presser immediately forward of the plow in the direction of the line of feed for pressing the fold initiated by the plow, the retainer, the plow and the fold presser being immovable relatively to one another in the direction of the line of feed.

26. The method of folding the margin of sheet material that comprises successively folding successive portions of the margin in one step through an angle of nearly one hundred eighty degrees, and pressing each folded portion while the next succeeding portion of the margin is being folded, thereby to relieve the stress in the material.

27. The method of folding the margin of sheet material that comprises feeding the material step by step, successively folding successive portions of the margin in one step through an angle of nearly one hundred eighty degrees when the said successive portions reach a predetermined position in the line of feed during successive pauses in the feed, and pressing each folded portion at a position immediately forward of the predetermined position in the line of feed during the next succeeding pause in the feed while the next succeeding portion of the margin is

being folded, thereby to relieve the stress in the material.

28. A machine of the class described having, in combination, a frame having an opening, a stationary knife having a stem mounted in the opening, a movable knife adapted to cooperate with the stationary knife, and means whereby the stem may be adjusted about its axis in the opening to adjust the position of the stationary knife.

29. A machine of the class described having, in combination, means for feeding material step by step, two means each adapted to vary the lengths of the steps of feed, means for cutting the material, and means operable to set into operation the cutting means and one of the feed-varying means to cut and vary the lengths of the steps of feed.

30. A folding machine having, in combination, means for folding the margin of material, means for slitting the margin prior to folding, means for feeding the material step by step to the slitting means and the folding means, two means each adapted to diminish the lengths of the steps of feed, and means operable to set into operation the slitting means and one of the means for diminishing the steps of feed, whereby the material may be fed by diminished steps of feed either with or without slitting.

31. A folding machine having, in combination, means for folding the margin of material, means for slitting the margin prior to folding, means for feeding the material step by step to the slitting means and the folding means, two means each adapted to diminish the lengths of the steps of feed, one of the diminishing means having a greater range of diminution than the other, and means operable to set into operation the slitting means and the diminishing means having a smaller range of diminution.

32. A folding machine having, in combination, means for folding the margin of material, a knife for slitting the margin prior to folding, means for feeding the material to the knife and the folding means, a continuously rotating member having an eccentric, a polygonal block mounted loosely on the eccentric, a member having an opening within which the polygonal block is mounted to slide freely, a link connecting the second-named member with the knife, means for holding the block against sliding movement in the opening to cause the second-named member to move with the continuously rotating member, means for releasing the holding means, and means tending to move the second-named member into a position such as to render the knife ineffective upon the release of the holding means.

33. A machine of the class described having, in combination, means comprising a feed point for feeding material, means for varying the feed, means for cutting the ma-

terial, means for controlling the feed point, means for controlling the feed-varying means, and means for controlling the cutting means, the three last-named means being under the control of widely separated parts 5 of the operator's body during the operation of the machine.

34. A folding machine having, in combination, a support over which material is 10 adapted to be fed, the support having a portion at one side of the line of feed inclined outward so as to bend the material outward, the incline increasing in the direction of feed and a folder for folding the material.

35. A folding machine having, in combination, a support over which material is 15 adapted to be fed, the support having a portion at one side of the line of feed inclined outward so as to bend the material outward, 20 the incline increasing in the direction of feed, a folder for folding the material, and a fold presser for pressing the fold.

36. A folding machine having, in combination, a support upon which material is 25 adapted to rest, the support having a marginal portion inclined outward towards the edge of the margin so as to bend the material outward, a plow for initiating a fold in the margin of the material pivoted to the 30 support near the said edge so as to move pivotally in a plane at right angle to the said edge, and means for pivotally actuating the plow.

37. A folding machine having, in combination, a support upon which material is 35 adapted to rest, the support having a marginal portion inclined outward towards the edge of the margin so as to bend the material outward, a plow for initiating a fold in the margin of the material, and means for actuating the plow transversely to the said edge, the plow having a nose adapted to engage the margin of the material and concavity adjacent to the nose, and the curve of the fold being adapted to seat in the concavity and against the inclined marginal portion of the support during the actuation of the plow 45 transversely to the said edge.

38. A folding machine having, in combination, a support, means for feeding material 50 over the support, the support having a marginal portion curved outward towards the edge of the margin so as to bend the material outward, a plow for initiating a fold in the margin of the material pivoted to the support near the said edge so as to move pivotally in a plane at right angles to the line of feed, means for pivotally actuating the 55 plow, the plow having a nose adapted to engage the margin of the material and a concavity adjacent to the nose, the curve of the fold being adapted to seat in the concavity and against the curved marginal portion of 60 the support during the pivotal actuation of 65

the plow, and a fold presser for pressing the fold initiated by the plow.

39. A folding machine having, in combination, a support upon which material is adapted to rest, a plow for initiating a fold in the margin of the material pivoted to the support so as to move pivotally in a plane at right angles to the support, means for pivotally actuating the plow in the said plane to initiate the fold, means for limiting the pivotal movement of the plow, and means yieldingly maintaining the plow in the limiting position of pivotal movement.

40. A folding machine having, in combination, a support upon which material is 70 adapted to rest, a plow for initiating a fold in the margin of the material pivoted to the support so as to move pivotally in a plane at right angles to the support, a fold presser for pressing the fold initiated by the plow, 75 and means yieldingly connecting the plow to the fold presser.

41. A machine of the class described having, in combination, an arm adapted to oscillate about a pivot, a link one end of which is 80 movable upon the arm along a line extending through the line of the pivot, a knife, the other end of the link being pivoted to the knife, and means for sliding the said one end of the link along the said line, whereby the knife is actuated when the said one end of the link is not in line with the pivot, and is not actuated when the said one end is in line with the pivot.

42. A machine of the class described having, in combination, an arm adapted to oscillate about a pivot, a member slidably upon the arm along a line extending through the pivot, and means for sliding the member upon the arm along the line during each oscillative movement of the arm.

43. A folding machine having, in combination, a support upon which material is adapted to rest, a plow for initiating a fold in the margin of the material pivoted to the support so as to move pivotally in a plane at right angles to the support, a fold presser for pressing the fold initiated by the plow, and means on the plow adapted to be engaged by the fold pressed to pivotally actuate the plow.

44. A folding machine having, in combination, a support, means for feeding material over the support, a knife for slitting the margin of the material, a retainer immediately forward of the knife and forward of the feeding means in the direction of the line of feed for holding the material against the support, a plow immediately forward of the retainer in the direction of the line of feed for initiating a fold in the margin of the material, and a fold presser immediately forward of the plow in the direction of the line of feed for pressing the fold initiated by the plow.

45. A folding machine having, in combination, means for feeding material, a support 120

for the margin of the material positioned at one side of the line of feed and inclined outward to bend the margin of the material outward, the incline increasing in the direction of the feed, a plow for initiating a fold in the margin of the material, and a fold presser for pressing the fold initiated by the plow.

46. A folding machine having, in combination, means for feeding material, a support for the margin of the material inclined outward to bend the margin of the material outward, a correspondingly inclined stationary knife separate from and situated forward of the support in the line of feed, and a movable knife for cooperating with the stationary knife.

47. A machine of the class described having, in combination, a rotatable member having an eccentric, a block mounted loosely on the eccentric, an arm having an opening within which the block is mounted to slide freely, and means for angularly adjusting the arm.

48. A folding machine having, in combination, means for folding the margin of material, a knife for slitting the margin prior to folding, means for feeding the material to the folding means and the knife, a rotatable member having an eccentric, a block mounted loosely on the eccentric, an arm having an opening within which the block is mounted to slide freely, a link connecting the arm to the knife, and means for angularly adjusting the arm.

49. A machine of the class described having, in combination, a member adapted to oscillate about a pivot and having a parallel-sided opening, a parallel-sided block loosely mounted in the opening, a knife connected to the member, and means for actuating the block to effect the oscillation of the member about the pivot, thereby to effect the actuation of the knife.

50. A machine of the class described having, in combination, a continuously rotating member, a member adapted to oscillate about a pivot and having an opening, a block loosely mounted in the opening, a knife connected to the second-named member, and means controlled by the first-named member for actuating the block to effect the oscillation of the second-named member about the pivot, thereby to effect the actuation of the knife.

51. A machine of the class described having, in combination, a member having an opening and a projection, a block loosely mounted in the opening, a knife connected to the member, and means comprising a cam adapted to engage the projection for actuating the member relatively to the block to effect the actuation of the knife.

52. A machine of the class described having, in combination, a continuously rotating member, a member adapted to oscillate about a pivot and having an opening, a block

loosely mounted in the opening, a knife connected to the second-named member, means whereby the continuously rotating member is normally ineffective to control the operation of the knife, and means whereby the continuously rotated member is adapted to cooperate with the second-named member to effect the actuation of the block to effect the oscillation of the second-named member about the pivot, thereby to effect the actuation of the knife.

53. A folding machine having, in combination, a support over which material is adapted to be fed, a folder for folding the material, a fold presser for pressing the fold, means for actuating the fold presser, the fold presser having a portion extending rearward in the line of feed and to one side of the folder, and means yieldingly maintaining the folder in engagement with the extending portion of the fold presser, whereby the folder is adapted to be actuated with the fold presser and is adapted to yield with respect to the fold presser during the actuation of the fold presser.

54. A folding machine having, in combination, a folder for folding material, a fold presser for pressing the fold, means for actuating the fold presser, and means carried by the folder adapted to be engaged by the fold presser to cause the folder to be actuated from the fold presser.

55. A folding machine having, in combination, a support, means for feeding material over the support, a retainer for holding the material against movement upon the support, and a folder for folding the material situated before the retainer in the line of feed.

56. A folding machine having, in combination, a support, means for feeding material over the support, a retainer forward of the feeding means in the direction of the line of feed for holding the material against the support, a folder immediately forward of the retainer in the direction of the line of feed for folding the material, the retainer and the folder being immovable relatively to each other in the direction of the line of feed, and a fold presser for pressing the fold.

57. A folding machine having, in combination, a folder for folding material, a fold presser for pressing the fold, and means for actuating the fold presser and the folder as a unit.

58. A folding machine having, in combination, a support over which material is adapted to be fed, a folder for folding the material, and a fold presser for pressing the fold, the fold presser having a portion extending rearward in the line of feed and to the left of the folder.

59. A folding machine having, in combination, a support, means for feeding material over the support, two means for folding the

material, and means for actuating the two folding means as a unit.

60. A folding machine having, in combination, a support, means for feeding material over the support, two means for operating on the material, and means for actuating the two operating means as a unit.

61. A folding machine having, in combination, a support, means for feeding material over the support, a fold presser for pressing a fold in the material, means for operating upon the material prior to the action thereon of the fold presser, and means for actuating the fold presser and the operating means as a unit.

62. A machine of the class described having, in combination, an arm adapted to oscillate about a pivot, a member slidable upon the arm along a line extending through the line of the pivot, means for sliding the member upon the arm along the line, and means for holding the pivot fixed during the sliding movement of the member upon the arm.

63. A folding machine having, in combination, a support over which material is adapted to be fed, a retainer for holding the material against the support, a folder for folding the material situated before the retainer in the direction of the line of feed, the retainer and the folder being immovable relatively to each other in the direction of the line of feed, and a fold presser for pressing the fold.

64. A folding machine having, in combination, a support over which material is adapted to be fed, a folder for folding the material, and a fold presser for pressing the fold, the fold presser and the folder being immovable relatively to each other in the line of feed, the fold presser having a portion extending rearward in the line of feed and to the left of the folder.

65. A folding machine having, in combination, means comprising a plurality of members for feeding material, means for varying the feed, means for cutting the material, means for controlling one of the feed members, means for controlling the feed-varying means, means for controlling the cutting means, the three last-named means being under the control of widely separated parts of the operator's body during the operation of the machine, and means for folding the material.

66. A folding machine having, in combination, means for feeding material, a folder for folding the material in one step through an angle of nearly one hundred eighty degrees, and a fold presser for pressing the fold produced by the folder.

67. A folding machine having, in combination, means for feeding material, a folder for folding the material in one step through an angle of nearly one hundred eighty degrees, means for actuating the folder to fold successive portions of the material each in one

step, a fold presser, and means for actuating the fold presser to press the folds successively produced by the folder.

In testimony whereof, I have hereunto subscribed my name this 9th day of July, 1923.

ANDREW R. RIDDERSTROM.
